ORTHOPTIC INSTRUMENT

George Bates Wootten, Sudbury, Ontario,
Canada

Application July 1, 1933, Serial No. 678,610

7 Claims. (Cl. 128—25)

My invention relates to improvements in orthoptic instruments and the object of the invention is to provide a single instrument in which is incorporated the various essential devices for overcoming non-pathological visual weaknesses or disturbances and it consists essentially of the arrangement and construction of parts as hereinabove more particularly explained.

Fig. 1 is a perspective view of my apparatus adapted for indicating the centre line of vision of each eye prior to treatment.

Fig. 2 is a similar view to Fig. 1 with the targets for treatment inserted in place of the indicating targets.

15 Figs. 3 and 4 are enlarged perspective details of the manual means for adjusting the targets.

Fig. 5 is a sectional view through a portion of the mechanism illustrated in Figs. 3 and 4.

Fig. 6 is a sectional detail showing the means 20 for adjusting the position of the driving motor.

Fig. 7 is a diagrammatic view showing how the virtual position of the target is displaced from the actual position.

Fig. 8 illustrates an alternative construction in 25 which prisms are employed in place of a reflector for displacing the position of the target.

Figs. 9 and 10 are enlarged sectional details of the construction shown in Fig. 8.

Fig. 11 is a diagrammatic view corresponding 30 to Figs. 8, 9 and 10 showing how the virtual position of the target is displaced from the actual position.

Fig. 12 is a perspective view of my device with a revolving target applied thereto.

35 Fig. 13 is a sectional view showing a drive for the revolving target.

Fig. 14 is a plan view of the motor shown in Fig. 13 and the reversing clutch.

40 Figs. 15, 16 and 17 are views of stationary targets and target carriers.

Fig. 18 is a detail view showing a means of interchanging the targets in the target carrier.

Fig. 19 is a detail of the driving gears shown in Fig. 4 and which engage the rack 37.

45 In the drawings like characters of reference indicate corresponding parts.

1 indicates the base of my machine the upper face of which is inclined to form a table 1'.

An arch 2 is provided with a horizontal portion 50 forming a head rest 3 having the nasal recess 4 and lens orifices 5 and 6 in which the lenses 5' and 6' are suitably secured. The sides 3' and 3° of the arch 2 (see Figs. 1 and 2) incline inwardly and are each provided on their inner face 55 with pockets for receiving targets as will herein-

after appear. The foot of each portion 3' and 3° resting upon and secured to the inclined table also forms a slotted opening 4'.

A pan 7 is inverted T shape in form, the lower edge of the inverted head being provided with an edge rib 7' the opposite edge of the arms of the T being provided with edge ribs 7°. The body of the inverted T extends upward and is provided with a central longitudinal slot 8 and slots 9 and 10 adjacent each edge of the T body. A securing bolt 8' extends through the central slot 8 and 9' and 10' securing bolts extending through the slots 9 and 10.

15 A square stud 11 is carried by the head rest. A mirror 12 is provided with a sleeve 12' through which extends a rectangular orifice in which fits the stud 11 being secured thereon by a set screw or other suitable device.

20 A slot 13 is formed in each end wall of the base 1. A bracket 14 is provided with a cylindrical upper end having a cylindrical orifice. The lower portion of the bracket 14 is preferably flattened and provided with a cross rib 14' fitting the slot 13 and slidable therein. A set screw extends through the lower portion of the bracket 25 14 and the slot 13 into clamping piece 16' which is also slidable in the slot 13 when the set screw 16 is loosened.

25 A standard 17 is provided with a cylindrical lower end turnably held in the cylindrical portion 30 of the bracket 14 and held in its adjusted position by a set screw 18. The standard 17 is provided with a horizontal upper end 17' terminating in a vertical bearing sleeve 17°, the lower portion of which is reduced as indicated at 17'.

35 A vertical shaft 19 is journaled in the bearing 17 and has secured to its upper end a bevel gear 20 and to its lower end a bevel gear 21.

An arm 22 is provided with a sleeve end 22' which is swung on the portion 17' to assume any 40 desired position in which it is held by the set screw 22°. A double bevel gear 23 is provided one portion of which meshes with the bevel gear 21. The gear 23 is mounted upon a stud shaft 23' carried by the arm 22.

45 The outer end of the arm 22 is provided with a bearing 24 from which extends an arm extension 24' having at its outer end a bearing 25. A shaft 26 is journaled in the bearings 24 and 25. A bevel gear 27 is secured to the shaft 26 at its 50 inner end and meshing with the other portion of the double gear 23.

55 A crown gear 28 is secured to the outer end of the shaft 26. A bracket 29 forms part of the extension 24' in which is secured a stud shaft 29' 55

on which is mounted a combined bevel and straight gear 30 and 31.

A hand wheel 32 is secured to a shaft 32^x journaled on a bearing 33 forming part of the standard 17. A bevel gear 34 is secured to the opposite end of the shaft 32^x and meshing with the bevel gear 20 hereinbefore referred.

A sliding member 35 has inscribed thereon some form of test objects such as the arrows 35^x and 35°.

A slide 36 is removably held on the slideways or pockets formed in the portions 3^x and 3°, and have inscribed thereon the arrows 36^x and 36°, which coact with the mirror 12 to assume a virtual position indicated by the dotted arrows in Fig. 1, the position of the rays producing this position being indicated in Fig. 7.

The slide 35 is movable longitudinally on the slideway formed by the parallel ribs 7^x and 7° and is provided with a rack 37 with which the straight gear 31 meshes.

In order to locate the location of the centre lines of vision, by means of imaginary lines extending between the actual position of the arrow 35^x and 25 the virtual image of the arrow 36^x indicated by dotted arrow and between the actual position of the arrow 35° and the virtual image of the arrow 36° indicated by the dotted arrow. I insert the slides 35 and 36 in their slideways as shown in 30 Fig. 1, the patient looking through the lenses 5^x and 6^x adjusts the position of the slide 35 by means of the hand wheel 32 until the arrow 35^x appears. The slide 36 is then adjusted until the virtual image of the arrow 36^x appears in transverse 35 alignment with the arrow 35^x. This virtual image of the arrow target 36^x on the slide 35 is produced by means of the mirror 12 reflecting the image of the arrow 36^x of the slide 36, such image reflected by the mirror then appearing to the eye 40 at 36^x on the slide 35 when viewed through the lens 5^x as illustrated in Fig. 7. In this figure the dashed line A represents the line of reflection of the arrow 36^x to its reflected position on the mirror 12. The dashed line B represents the line 45 of vision from the lens 5^x to the reflection of the image in the mirror 12 and the dotted line C, which is the line B produced, an imaginary line of vision along which the virtual image appears at 36^x on the slide 35 thus displacing the visual 50 perception of the stationary target from its actual to its virtual position. The position of the slide is then noted on the graduations 38 which indicates the position of the centre line of vision transversely. The apparent position of the arrow 55 36° on the slide 35 is obtained in the same manner as described in connection with the arrow 36^x. The slide 35 is also adjusted manually until the arrow 35° is in a line with the virtual image of the arrow 36° which position is indicated by the 60 graduations 38 (see Fig. 1).

I will now refer to Fig. 2. After the position of the centre lines of vision have been found as above described their point of intersection being the position of rest, and the positions on the graduated scales 38 and 38^x noted, the slides 35 and 36 are withdrawn from their guideways and replaced by similar slides 39 and 40 which form carriers for the targets 41 and 42 which are in the form of a spot on a black ground so that all other 65 points but the target in the field of vision are black thus providing a target having a maximum intensity of light rays, such intensity being varied by the incandescent lights indicated at 43 and 44 operated by a rheostat control switch which I 70 have not shown being commonly used.

The slides 39 and 40 are provided with graduated scales 39^x and 40^x which correspond to the scales 38 and 38^x so that the targets 41 and 42 may be placed immediately and accurately in the position of rest without any voluntary or involuntary effort on the part of the patient which might tend to visual suppression to bring about fusion, before the targets are accurately in position.

After the position of the centre lines of vision 10 have been found means may be provided for building up the mental power of the patient to fuse objects. This may be done in various ways either by providing a stationary target of one color and the movable target of another contrasting color so that when the centre lines of vision are in a position of rest these colors should blend to form a secondary color. If the colors do not blend it is an indication that the sight of one eye is being suppressed and that the other 20 eye functions alone and therefore only one color is seen.

By the use of two targets of contrasting color one before either eye together with variable illumination for either target provides a new 25 means of creating, measuring and developing fusion consciousness.

Similar results may be obtained by employing a stationary target and a revolving target as illustrated in Figs. 12, 13 and 14. In these figures 30 45 is the target carrier having longitudinal edge ribs to form a clearance space between the surface of the table and the target carrier. An aperture 45^x is formed in the carrier and a bearing, 45° is located centrally beneath the aperture. A 35 shaft 46 is journaled in the bearing 45° the upper end of which may be square. A disc 47 is provided with a hub 47^x having a squared orifice into which the squared end of the shaft 46 fits. A driving shaft 48 is mounted in bearings 49 carried by the carrier 45. A bevel gear 50 is secured on the shaft 46 and 51 is a bevel gear secured on the shaft 48 and meshing with the bevel gear 50. The numeral 52 indicates a driving motor and 53 the motor shaft on which is slidably 45 mounted the sleeve 54 feather keyed to the shaft. The direct and reverse drive gears 55 and 56 are carried by the sleeve 54. A short shaft 57 is journaled in a bearing 58 and connected by a flexible shaft 59 to the shaft 48. A bevel gear 60 is secured to the shaft 57 and meshing either with the gear 55 or 56 as the sleeve 54 is moved in either one direction or the other by the lever 61.

In using this device after the point of convergence has been found as above described the target carrier 45 and target 47 is inserted coacting with a stationary target such as indicated at 42, Fig. 2.

If there is no suppression of the poorer eye the 60 revolving target will be seen revolving in a superimposed position over the reflected stationary target. If the poorer eye is suppressed the reflected stationary target will alone be seen.

The effort on the part of the patient to see the 65 revolving target tends to increase his fusional faculty. In order to adapt to the position of rest of eyes which are extremely divergent or convergent I may use targets illustrated in Figs. 15 and 17, thus providing for a far greater outward 70 or inward deviation.

The targets used are white spots on a black ground to give the maximum amount of light stimulus to the eye. The movable target 42 and its carrier is then reciprocated by means of the 75

motor 52^x, the shaft 53^x of which (see Fig. 2) is provided with a disc 62 secured thereto and provided with a radial row of holes 62^x. A pitman rod 63 is pivotally connected to the end of the carrier 40 as indicated at 64 and connected to the disc at its opposite end by a crank pin 65 secured in any one of the holes 62 in accordance with the length of the stroke desired.

As soon as fusion is experienced by the patient 10 use is made of the hand control operating the sliding target to slightly displace it from the position of rest. As fusional range is developed we can then exercise within that range by means of the motor.

15 By the reciprocating of the movable target the fused stationary and movable targets tend to break away, the reciprocating movement of the target being at first very short so as to gradually train the eyes to hold the fusion. The movement 20 is gradually increased to lengthen the stroke until the eyes are brought back beyond the position of normal convergence, thereby strengthening the muscles until they are able to function normally and at the same time build the reserve so that 25 they are enabled to carry out these functions comfortably.

In cases where there is vertical imbalance between the two eyes the operation is the same. The position of the targets is adjusted up or 30 down. That is in case of the left eye being higher the stationary target may be adjusted upward or the movable target downward and in the case of the right eye being higher the movable target may be adjusted upward or the stationary target 35 downward.

40 In order to gradually exercise the eye when there is vertical imbalance the tray, by loosening the nuts 9^x and 10^x, may be adjusted to an inclined position so the target carrier 40 and target 42 may be reciprocated in an inclined direction thereby permitting a very small range of vertical displacement in association with the longitudinal movement so that the eye can be trained very gradually back to normal.

45 Together with the above results provision may be made for the use of stereoscopic pictures, as an auxiliary method of treating suppression, while providing adaptation of either picture vertically or horizontally to compensate for any muscular imbalance between the two eyes. A 50 large inward displacement is provided by the mirror in front of one eye and the vertical adjustment by the raising and lowering of either picture.

55 An auxiliary method may be provided for treating amblyopia by using the large rotating disc before that eye with the septum in place and the light completely shut off from the better eye. This is also used to develop motility of the muscles in an eye which, through disuse, has lost 60 the function of the muscles.

When this method is employed a septum 66 is provided supported on the stud 11^x (see Fig. 12). A large disc 47^x is mounted on the stud 65 shaft 46 illustrated in Fig. 13. The position of the carrier is adjusted so that the disc is on one side of the septum and is driven by the mechanism illustrated in Fig. 13. A target 47^x is placed on the disc as indicated.

70 By removing the septum and adjusting the target carrier so that the disc 47^x assumes a central position an auxiliary method is provided for exercising, binocularly, muscular incoordination.

75 Another auxiliary method for treating, binocularly, muscular incoordination is to place the

two targets beyond the fusional range, gradually moving them towards easier fusion positions. This stimulates the eyes to move in the desired direction in order to produce fusion of the two images.

In order to adjust the position of the motor so that the movement of the target will be from any fusional point at which the targets are set, I mount the motor on a slide 68 to compensate for the vertical position of fusion point of the 10 targets, the slide being provided with a transverse slot in which the motor is adjusted by means of the nut 69 (see Fig. 6) to compensate for the horizontal position of the fusion point.

By means of the targets illustrated in Figs. 15, 15 16 and 17 exercises may be provided with the eyes directed centrally or both to one side or the other, or both raised or both lowered.

In Figs. 8, 9, 10 and 11 I show an alternative construction in which I employ prisms instead 20 of a reflector for displacing the actual position of the target to a virtual position to conform to the normal convergence of the central lines of vision. In this construction I employ beneath the lenses 5^x and 6^x prisms 70 and 71 held in a. 25 frame 72 which is pivoted on the lens holding ring 73 and adjustably held in a spring catch so that prisms of various thickness may be employed. A septum 74 divides the field of vision centrally between the eyes. In this construction the stationary target carrier 79 is supported upon the table in longitudinal alignment with the movable target carrier 80 so as to coact with the prisms. 30

35 By this means in cases of high divergence the prisms afford a greater field for outward displacement of the targets. Also by the use of the prisms ordinary stereoscopic pictures and charts may be used without the picture being reversed or laterally transposed as is necessary with the mirror. The targets may be removably held in the 40 target carrier as indicated in Figure 18. In this figure 75 is the target and 76 the carrier. The lower portion of the target is extended annularly to form a surrounding flange 75^x. The target carrier is provided with an aperture 76^x, the lower 45 portion of which is enlarged to the diameter of the target flange 75^x to form a flange 76^x against which the flange 75^x fits when the target is inserted. In the enlarged portion of the orifice 76^x is an annular groove 77 containing a split 50 spring retaining ring 78 engaging the lower face of the flange 75^x. By this means the targets may be interchanged whenever desired.

55 From this description it will be seen that I have devised an instrument by which all treatments which are desirable and essential for the improvement of the vision may be given and the form of the several steps of treatment varied to relieve the monotony, to more effectively arouse the interest of the patient therein, which provides a 60 greater flexibility of technique for the practitioner, which provides more effective means for carrying out each step and combines in one unit the various devices to be used. The development of the coordinated functions are built up simultaneously and by more effective means, in which the indicating of the centre lines of vision is effected so that the targets may be seen without strain on the eyes of the patient, in which the movement of the target may be effected by direct 65 manual means or through the medium of a hand wheel or by means of a driving motor such as illustrated.

What I claim as my invention is:

1. In a device for treating eyes, the combina- 75

tion with a table, a head rest and a lens for each eye mounted in the head rest, of a stationary target coacting with one lens, a movable target coacting with the other lens, means for displacing visual perception of the stationary target from its actual to an apparent position to coact with the position of visual perception of the movable target in its actual position, a target carrier for the movable target, a motor and 10 motor shaft, a driving connection between the shaft and carrier for reciprocating the carrier, adjustable means for controlling the length of stroke of the movable target, and means for adjusting the position of the motor transversely to correspond with the transversely set position of the target.

2. In a device for treating eyes, a table, a head rest, a lens for each eye carried by the head rest, graduated means for locating on the table a point corresponding to the point of convergence 20 of the axes of the eyes, a stationary target viewed through one lens, a target movably mounted on the table and viewed through the other lens, means for producing a virtual image of the stationary target located in the same plane as the movable target, and a scale coacting with each target, the graduations of which correspond to the graduations of the aforesaid convergence point locating means whereby the centre of the 25 movable target and the virtual image of the stationary target automatically coincide with the previously located point of convergence when placed in the same graduated position.

3. In a device for treating eyes, a lens support, a lens mounted in the support and coacting with one eye, a table, a stationary slide extending edgewise between the table and lens support and on which a target is represented, a movable slide mounted on the table to move transversely to the stationary slide and on which 40 a target is represented, a lens also mounted in the lens support and coacting with the other eye, and a mirror coacting with the first mentioned lens and target to provide, on the movable slide, a stationary virtual image of said first mentioned target to coact with the target of the movable slide.

4. In a device for treating eyes, the combination with a table forming a slide support, a head rest and lenses mounted in the head rest, of 50 means for indicating on the table the point of convergence of the axes of the eyes, such means comprising a stationary and a movable slide set at an angle one to the other, pointers extending from two adjacent sides of the stationary slide and viewed through one lens, similar pointers extending from the complementary sides of the

5 movable slide and viewed through the other lens, means for producing a virtual image of the pointers of the stationary slide on the movable slide in a line with the pointers of the movable slide, and graduations for indicating the position of the aforesaid indicating slides when indicating the point of convergence of the axes of the eyes, a stationary and a movable exercising target slide, each having a spot target thereon and adapted to replace the aforesaid indicating slides 10 and bearing graduations identical to those of the indicating slides so that the centres of the spot target of the movable slide, the virtual image of the spot target of the stationary slide and the indicated point of convergence are coincident 15 when the spot target slides, and convergence indicating slides are set in the same graduated position.

5. In a device for treating eyes, the combination with a table, a movable slide mounted on 20 the table, and a head rest and lenses mounted thereon, of a disc revolvably mounted on the slide and forming a dark background, a relatively bright spot target located eccentrically on the 25 face of the disc, and means for rotating the disc in all positions of the movable slide.

6. In a device for treating eyes, means for 30 locating the point of convergence of the axes of the patient's eyes, a stationary target, means for producing a virtual image of the stationary target in such a position as to be viewed by one eye, means for instantly and accurately locating such virtual image in a position coincident with the previously formed point of convergence, and 35 a movable target viewed through the other eye, and means for instantly and accurately placing the centre of the movable target in an initial position coincident with the centre of the virtual image and the point of convergence in and out of which position it is adapted to be intermittently 40 moved.

7. In a device for treating eyes, means for 45 locating the point of convergence of the axes of the patient's eyes, a stationary target, means for producing a virtual image of the stationary target in such a position as to be viewed by one eye, means for instantly and accurately locating such virtual image in a position coincident with the previously formed point of convergence, and 50 a movable target viewed through the other eye, and means for instantly and accurately placing the centre of the movable target in an initial position coincident with the centre of the virtual image and the point of convergence, and means for intermittently moving the movable target in and out of its position of coincidence.

GEORGE BATES WOOTTEN.
